UNITED STATES PATENT OFFICE.

RUSSELL FRANKLIN COLLINS, OF SPOKANE, WASHINGTON.

GRAVITY ORE-CRUSHER.

1,118,474.

Specification of Letters Patent. Patented Nov. 24, 1914.

Application filed January 31, 1914. Serial No. 815,669.

To all whom it may concern:

Be it known that I, RUSSELL F. COLLINS, a citizen of the United States, residing at Spokane, in the county of Spokane and

5 State of Washington, have invented a new and useful Gravity Ore-Crusher; and I do hereby declare the following to be a full, clear, and exact description of the invention, such as will enable others skilled in the art 10 to which it appertains to make and use the same.

This invention relates to a new and useful improved ore crushing machine, of that type in which the ore is first rotated around 15 with the cylinder partially, and then falls against a central axle or shaft or spindle, which is supplied with a plurality of sharp pointed or jagged picks or teeth. As the ore falls against this axle or shafting, it is thoroughly broken and crushed by said picks. 20 As the ore leaves the axle or shaft and falls against the inner circumference of the cylinder under the axle the same is further broken and crushed by the teeth of the cylinder.

25 One of the features of the invention is that the axle or shaft comprises a core member having a series of bands, from which the sharp jagged points extend.

30 Another feature of the invention are the rake-like teeth of the inner circumference of the cylinder, which teeth are slightly curved in the direction in which the cylinder rotates, for the purpose of conveying the 35 larger and heavier portions of ore or quartz to a position relative to the axle or shaft where the same may be dropped or dumped upon the large central axle, thereby crushing and breaking the ore by the jagged 40 point, and after falling to the bottom of the cylinder again, they are picked up and returned, in order to be dropped upon the central axle again. This process continues as long as the cylinder is revolved, or until the 45 ore is ground to the desired mesh.

Another feature of the invention is the provision of outlets for the crushed ore, said outlets having perforated plates, and movable perforated plates adjustable with relation to the first plate, whereby the perforations may be enlarged or restricted, so as to permit of the discharge of different grades of crushed ore.

In practical fields the details of construction may be subjected to alterations, falling 55 within the scope of what is claimed.

The invention comprises further features and combination of parts, as herein-after set forth, shown in the drawings and claimed.

In the drawings: Figure 1 is a view in perspective of the cylinder showing the central axle or shaft applied. Fig. 2 is a longitudinal sectional view on line 2—2 of Fig. 1. Fig. 3 is a transverse sectional view on line 3—3 of Fig. 1. Fig. 4 is a detail view, showing the co-operating perforated plates of the discharge opening. Fig. 5 is a detail view showing the jacket 7.

Referring more particularly to the drawings, 1 designates the cylinder, which may be constructed of any suitable material and in any suitable proportions. This cylinder is constructed of beam sections 2 fitted together to form a perfect cylinder, said sections being preferably wood or other suitable fiber. The heads 3 and 4 of the cylinder are likewise constructed of wood or other suitable fiber, of tough quality. The inner circumference of the cylinder may be lined throughout with cement, heavily reinforced with scrap iron of various kinds, the cement being designated by the numeral 5 and the scrap iron designated by the numeral 6; or the inner circumference may be incased in a jacket 7, as shown in Fig. 5, of malleable iron or steel constructed of blocks or castings. The inner circumference of the cylinder is constructed with sharp points or spurs, secured to the outer wall of the cylinder as shown at 8, said points or spurs being designated by the numeral 9, and are slightly curved in the direction in which the cylinder rotates or revolves. Said points or spurs project through the lining of cement and scrap iron or steel in one instance, and in another they project from the incasement of steel or iron. At a suitable location the wall of the cylinder is constructed with an opening 10 having a closure 11, which may be removed so that the ore and the like may be placed in the cylinder. Also arranged at suitable locations in the wall of the cylinder are openings 12 having stationary perforated plates, said perforations being of a triangular contour as shown. Co-operating with the stationary perforated plate are movable perforated plates 13, the perforations of which are of a contour corresponding with the perforations of the stationary plates, but reversely arranged. The movable perforated plate may be adjusted,

105 110

so as to bring the perforations of the movable plates in and out of registration with the openings to which the ore is inserted into as to permit of the discharge of different 5 meshes of crushed ore. The proportions of the openings to which the ore is inserted into the cylinder and the proportions of the openings with the perforated plates may be varied to suit the requirements. The contour 10 and construction of the teeth, points or spurs of the cylinder may be changed to suit the requirement relative to the kind of ore to be handled.

Mounted in bearings of the heads of the 15 cylinder is a shaft or axle 15, which comprises an inner core 16 of any suitable material preferably wood or other fiber of tough quality, which is incased in sections of steel jackets or sleeves 17 having short points, 20 spurs or picks 18 radiating therefrom, in contact with which the ore is forcibly thrust, so as to be crushed or broken in small particles, said ore falling from the inner circumference of the cylinder. The inner core is 25 provided with pintles 19 at its ends projecting beyond the sleeves or jackets of the core. These pintles are incased in steel or brass jackets or sleeves 20, which in turn are mounted in roller bearings 21 as shown.

30 The outer circumference of the cylinder at one end is provided with a band of gear teeth 23, to which any suitable power may be geared by the gear 24, so as to impart a revoluble movement to the cylinder. As the 35 cylinder revolves the ore is carried around therewith to a location over the central shaft or axle, where it is released and thrust with force down upon the sleeve castings or jackets of the shaft in contact with the 40 sharp points thereof, then falling from the axle in contact with the points or spurs of the lower portion of the cylinder. In this manner the fragments of ore are sufficiently reduced, so that the finer mesh will pass 45 through the perforations of the stationary and movable plate. When the ore is dropped from the axle to the lower portion of the cylinder, it is again picked up and carried to a location above the axle, where it is 50 again released and thrust down against the

axle. The cycles of operations are consecutively repeated until the desired mesh of ore is attained.

The invention having been set forth, what is claimed as new and useful is:

1. In combination, a revoluble cylinder provided with an ore pulverizing interior surface, a shaft on which said cylinder is mounted and having sectional pulverizing means coöperating with the first pulverizing 55 means for crushing the ore, said cylindrical wall of the cylinder being constructed of longitudinal beam sections arranged in sequence and removably united, said cylinder having cylinder heads comprising segmental sections removably joined in sequence and radiating from said shaft, said heads acting as means to hold the sectional pulverizing means on the shaft, and means for holding the beam sections of the cylindrical 60 wall together.

2. In combination, a revoluble cylinder provided with an ore pulverizing interior surface, a shaft on which said cylinder is mounted and provided with a plurality of 65 steel jackets arranged axially on said shaft, each jacket having ore agitating or pulverizing means, said cylinder having cylinder heads for holding said jackets in sequence and axially on the shaft.

3. In combination, a revoluble cylinder comprising an outer casing having a plurality of sharp teeth or spurs, and an inner casing composed of cement and scrap metal, an axle mounted in bearings of the cylinder 85 heads of the cylinder and provided with pulverizing means, the teeth of the cylinder being curved in the direction of rotation of the cylinder, whereby the ore may be carried to a location substantially above the 90 axle so that the ore may be thrust by gravity down upon the pulverizing means thereof.

In testimony whereof I have signed my name to this specification in the presence of two subscribing witnesses.

RUSSELL FRANKLIN COLLINS.
